Primary Examiner — Thomas Johannes*Assistant Examiner* — Catherine Posthauer(74) *Attorney, Agent, or Firm* — Knobbe, Martens, Olson & Bear, LLP(57) **CLAIM**

The ornamental designs for an umbrella hub, as shown and described.

DESCRIPTION

FIG. 1 is a perspective view of the umbrella hub, shown in a usage environment;

FIG. 2 is a bottom perspective view thereof, with the environment removed for clarity of details;

FIG. 3 is a front view thereof;

FIG. 4 is a right side view thereof;

FIG. 5 is a top view thereof; and,

FIG. 6 is a bottom view thereof.

The broken lines in FIGS. 1-6 depict portions of the umbrella runner that form no part of the claimed design.
